S. J. WENTWORTH.

MACHINE FOR PREPARING AND SHAPING THE BOTTOMS OF LASTED SHOES.

APPLICATION FILED MAY 27, 1916.

1,297,426.

Patented Mar. 18, 1919.

INVENTOR

Samuel J. Wentworth
By his Attorney
Edward M. Howard

UNITED STATES PATENT OFFICE.

SAMUEL J. WENTWORTH, OF NEWPORT, KENTUCKY, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR PREPARING AND SHAPING THE BOTTOMS OF LASTED SHOES.

1,297,426.

Specification of Letters Patent. Patented Mar. 18, 1919.

Application filed May 27, 1916. Serial No. 100,311.

To all whom it may concern:

Be it known that I, SAMUEL J. WENTWORTH, a citizen of the United States, residing at Newport, in the county of Campbell and State of Kentucky, have invented certain Improvements in Machines for Preparing and Shaping the Bottoms of Lasted Shoes, of which the following description, in connection with the accompanying drawings, 10 is a specification, like reference characters on the drawings indicating like parts in the several figures.

This invention relates to machines for operating on shoes and more particularly to a 15 machine for preparing and shaping the bottom of a lasted shoe.

In the manufacture of shoes in which the upper leather has a glossed or enamel-finished surface such as "patent leather" considerable difficulty is experienced in using cement to attach other parts of the shoe to the upper because of the impervious character of the finished surface of the leather. 20 One instance which may be considered as 25 illustrative of this difficulty is in the manufacture of shoes having a patent leather upper and a wood heel. According to the present method of making these shoes the wood heel is temporarily attached to the 30 shoe by cement and after the cement has "set" sufficiently to prevent the heel from being displaced the heel is nailed on the shoe. The step of initially attaching such heels by cement is of particular importance because 35 wood heels are of the final shape when applied to the shoes, and, therefore, must necessarily be applied with exactness as contrasted with leather heels which are trimmed down to the proper finished shape after 40 they are nailed to the shoe; also proper initial attachment of wood heels facilitates the final heel attaching operation which would otherwise be extremely difficult because of 45 the characteristic shapes of wood heels. 50 When the cement is applied to the impervious surface of the overlasted portion of the upper at the heel seat it does not adhere sufficiently to the leather and consequently allows the heel to slip and be improperly attached during the nailing operation.

Also the heel seat of the lasted shoe is often more or less uneven and irregular owing to the plaits and folds in the upper resulting from the lasting operation so that

the heel seat does not present a satisfactory surface to receive the heel of the shoe. 55

A general object of the present invention is to provide a novel machine for treating the finished surface of an enameled leather shoe upper, whereby the difficulty experienced in using cement to attach other parts of the shoe to the shoe upper may be eliminated. 60

In the illustrated preferred embodiment of the invention, a machine is provided by 65 which the finished surface of the overlasted portion of the upper at the heel seat of a shoe can be rendered pervious to the cement employed in attaching a wood heel. In accordance with this embodiment of the invention, as shown, the machine comprises a tool 70 constructed and arranged to act upon the overlasted portion of the upper at the heel seat and has provision for heating the tool to a temperature sufficient "to sear" the finished surface of the leather acted upon by the tool. 75

In accordance with a further feature of the invention, the tool is so formed and arranged that it can be manipulated to iron 80 down the plaits of the upper at the heel seat and level off the heel seat to insure the proper attachment of a wood heel to the shoe. 85

These and other objects and features of 85 the invention will be apparent from the following detailed description read in connection with the accompanying drawings and the various novel features of the invention are set forth in the appended claims. 90

In the drawings,

Figure 1 is a side elevation of a preferred embodiment of the machine of the present invention;

Fig. 2 is a plan view of the shoe positioning means; and

Fig. 3 is a plan view of the tool for operating upon the shoe.

The illustrated machine comprises a supporting column 2 in which is mounted for 100 vertical sliding movement a post 4. The post is normally held in raised position in the column by a coiled spring 6 which surrounds the post and is interposed between an adjustable collar 8 on the post and a 105 shelf 10 formed on the base of the column. The post 4 is moved downwardly in the column 2 against the tension of the spring

6 by a foot treadle 12 pivoted at 14 to the lower end of the post and fulcrumed at its rear end on a stud 16 in the column. Adjustably mounted on the upper end of the 5 post 4 is a horizontally extending presser arm 18 which carries at its outer end the tool for operating upon the shoe and the means for heating the tool. The shoe is supported for the operation of the tool upon 10 a work support comprising a supporting post 20 pivoted at its lower end on a stud 22 mounted in lugs 24 projecting from the column for tipping movement toward and from the operator. The upper end of the 15 post is provided with a last pin 26 formed on a block 28 which is pivoted on a stud 30 having bearings in the post and extending longitudinally of the shoe to permit transverse tipping movement of the 20 shoe on the work support. The shoe is positioned and held in operative relation to the tool by a heel embracing band or clamp 31 which automatically adjusts itself to the particular size of shoe to be operated 25 upon and centers the shoe relatively to the tool. As herein shown, the heel clamp 31 comprises two L-shaped levers 32 and 34 adjustably mounted upon vertically and parallelly disposed rods 36 and 38, respectively, 30 which have their upper ends received in bearings in the presser arm 18 and their lower ends confined in lugs 40 projecting from the column. The arms 42 and 44, respectively, of the levers 32 and 34 project 35 toward each other and are provided with cooperating rack teeth 46 whereby the opening and closing movements of the heel clamp are equalized. The forward ends of the levers are adapted to embrace the heel end 40 of a shoe and are normally maintained in position to embrace the smallest size shoe to be operated upon by torsion springs 48 surrounding the rods 36 and 38 and confined between the hubs on the levers 32 and 45 34 and the lugs 40 on the column.

In order to confine the action of the tool to the overlasted portion of the upper of shoes of different sizes the tool for operating upon the shoe is constructed and arranged 50 for automatic adjustment according to the particular size of shoe to be operated upon and as herein shown the adjustment of the tool is effected through connections with the heel clamp. To this end the 55 tool comprises two metal blocks 50 and 52 each shaped approximately to the outline of one half of the heel portion of a shoe and having bottom faces adapted to conform to the heel seat of a lasted shoe. These blocks 60 50 and 52 are removably secured by nuts 54 to the outer ends of arms 56 and 58, respectively, which are pivotally mounted at their rear ends upon the rods 36 and 38. In order that the tool may partake of the movement of the heel clamp when it embraces 65

the heel end of the shoe bosses 60 are provided on the levers 32 and 34 intermediate their ends, the bosses receiving the lower ends of rods 62 and 64 the upper ends of which are held for sliding movement in 70 lugs 66 on the arms 56 and 58 supporting the tool.

The outer end of the presser arm 8 is provided with a horizontal recess adapted to receive an electrical heating unit 68 75 which is connected by wires 70 to any suitable source of current. The upper portion of both blocks 50 and 52 are preferably recessed to receive or inclose the lower portion 72 of the heating block in which the 80 heating unit 68 is located so that the heating tool may be quickly brought to the proper degree of heat and maintained at such temperature when adjusted for shoes of different sizes. 85

In the use of the apparatus, the lasted shoe is first mounted upon the last spindle 26 and then moved into position to be embraced by the heel band 31, the torsion springs 48 on the rods 36 and 38 acting 90 normally to maintain the heel band closed. The movements of the levers 32, 34 of the heel band to accommodate the heel end of the shoe effect a similar adjustment of the blocks 50, 52 through their rod connections 95 62, 64 whereby the tool may act upon the overlasted portion of the upper according to that particular size of shoe. The electrical heating unit 68 is then utilized to heat the tools 50, 52 to a temperature sufficient to 100 sear the finished or enameled surface of the leather and render it pervious to cement. It is important that the heat of the tool is not sufficient to destroy or decompose the body of the leather but merely enough to 105 sear or decompose the finish on the surface of the leather. It has been found that in practice a heat of 190° F. will be sufficient to effect the desired result on the finished surface of patent or enameled leathers. Upon 110 depression of the treadle 12 the presser arm 18 and the tools 50, 52 are moved downwardly on to the heel seat of the lasted shoe whereupon the overlasted portion of the upper is subjected to the heat of the tools 115 which destroys the impervious finish of the leather so that the cement used in attaching the wood heel to the shoe can penetrate the body of the leather and become properly attached thereto. By causing the heated 120 tool to exert considerable pressure on the heel seat the plaits and folds of the upper which were caused by the heel seat lasting operation are also ironed down and the heel seat conformed to the shape of the last 125 bottom and the bottom face of the tool. While the invention has been herein described as embodied in an apparatus for operating on the heel seat of a lasted shoe it is apparent that the broad features there- 130

of may be advantageously embodied in an apparatus for operating on other portions of the shoe wherein similar results are desired.

5 Having thus described my invention, I claim as new and desire to secure by Letters Patent of the United States:—

1. A machine for operating upon shoes having, in combination, a die constructed 10 and arranged to act upon the finished surface of the overlasted portion of a shoe upper on the bottom of the shoe, means for heating the tool to a temperature sufficient to cause searing of the finished surface of 15 the overlasted portion of the upper, and means for relatively guiding the shoe and the tool into operative relation.

2. A machine for operating upon shoes, having, in combination, a tool constructed 20 and arranged to act upon the finished surface of the overlasted portion of the shoe upper at the heel seat, means for heating the tool to a temperature sufficient to cause the surface of the upper acted upon to be 25 rendered pervious to cement, and means for relatively guiding the shoe and the tool into operative relation.

3. In a machine for operating upon shoes, the combination with means for supporting 30 a lasted shoe, of a heated tool adapted to sear the outer surface of the overlasted portion of the leather at the heel seat of the shoe to render it pervious to cement, and means for effecting a relative movement between 35 said supporting means and said tool in a direction substantially perpendicular to the bottom of the shoe.

4. In a machine for operating upon shoes, the combination with means for supporting 40 a lasted shoe, of a tool constructed and arranged to act upon the overlasted portion of the upper at the heel seat, means for heating the tool to cause the surface of the upper acted upon to be rendered pervious to cement, and means for effecting a relative movement between said supporting means 45 and said tool.

5. In a machine for operating upon shoes, the combination with means for supporting 50 a lasted shoe, of a tool constructed and arranged to engage the overlasted portion of the shoe upper at the heel seat, means for moving the tool into operative relation to the shoe, and means for heating the tool to 55 a temperature sufficient to sear the finished surface of the upper and to render it pervious to cement.

6. A machine for operating upon shoes having, in combination, a shoe support, a tool constructed and arranged to engage the heel seat of a lasted shoe, means for heating the tool, and means operating to force the heated tool against the heel seat with sufficient pressure to cause it to conform to 65 the contour of the heel seat of the last.

7. A machine for operating upon shoes having, in combination, means for supporting a lasted shoe, a tool having an acting face shaped to conform the heel seat of the shot to the contour of the heel seat of the 70 last, means for heating the tool, and means for effecting a relative movement between the shoe and the tool for causing the heel seat of the shoe to be subjected to a shaping and conforming action by said tool. 75

8. A machine for operating upon shoes having, in combination, means for supporting a lasted shoe, a tool having an acting face contoured to correspond substantially to the contour of the heel seat of the last, 80 means for heating the tool, and means constructed and arranged to cause the heated tool to subject the heel seat of the shoe to the molding action of said tool.

9. A machine for operating upon shoes 85 having, in combination, a support for a lasted shoe, a tool having its acting face shaped to correspond to the shape of the heel seat of the last, means for adjusting said tool to the heel seats of shoes of various sizes, and 90 means for causing the heel seat of the lasted shoe to be subjected to a shaping and molding action by the tool.

10. A machine for operating upon shoes having, in combination, a tool constructed 95 and arranged to act upon the finished surface of the overlasted portion of the shoe upper at the heel seat, means for heating the tool to a temperature sufficient to render the surface of the upper acted upon pervious 100 to cement, means for presenting the shoe in position to be acted upon by the tool, and means for moving the tool into operating relation on the shoe.

11. A machine for operating upon shoes 105 having, in combination, a work support for supporting a lasted shoe, a heel band arranged to adjust itself automatically to different sizes of shoes, a tool adapted to act upon the overlasted portion of the upper at the heel seat and constructed and arranged for automatic adjustment according to the size of the shoe being operated upon, means for heating the tool to a temperature sufficient to sear the finished surface of the 115 leather acted upon, and means for relatively moving the tool and the support into position for the action of the tool upon the upper.

12. A machine for operating upon shoes 120 having, in combination, a support for a lasted shoe, a heel band arranged to adjust itself automatically to different sizes of shoes, a reciprocable tool adapted to act upon the overlasted portion of the upper 125 at the heel seat and connected with the heel band for automatic adjustment thereby according to the size of the shoe being operated upon, means for heating the tool to a temperature sufficient to sear the finished 130

- 4
- surface of the leather acted upon, and treadle operated means for relatively moving the tool into position to act on the work to effect the desired operation upon the upper.
13. A machine for operating upon shoes, having, in combination, a work support for supporting a lasted shoe, a vertically movable heel band arranged to adjust itself automatically to different sizes of shoes, a reciprocable tool adapted to act upon the overlasted portion of the upper at the heel seat, connections between the heel band and the tool for adjusting the tool to the size of shoe embraced by the heel band, means for heating the tool to a temperature sufficient to sear the finished surface of the leather acted upon, and treadle operated connections to the tool for moving the tool into position to act upon the upper.
14. A machine for operating on shoes having, in combination, a support for a lasted shoe, a tool having its acting surface shaped to correspond substantially to the shape of the heel seat of the shoe last, means for engaging opposite sides of the shoe at the heel and arranged to adjust itself to shoes of various sizes, connections between
- the said tool and the said shoe engaging means operating to adjust the tool to the size of the shoe engaged by the shoe engaging means, and means for relatively guiding the tool and the shoe into operative relation.
15. That improvement in methods of preparing the heel seats of shoes to receive heels, which consists in subjecting the heel seat surface of a shoe to the pressure of a mold the acting surface of which corresponds substantially in contour to the contour of the heel seat surface of the last, and simultaneously subjecting the heel seat materials of the shoe to the action of heat to render them more susceptible to the shaping pressure of the mold.
16. That improvement in methods of preparing the heel seats of shoes to receive heels, which consists in shaping the entire heel seat of a shoe to the contour of the shaping faces of a die in the presence of heat by forcing the heated die against the heel seat of the shoe in a direction substantially perpendicular to the plane of the shoe bottom.

In testimony whereof I have signed my name to this specification.

SAMUEL J. WENTWORTH.
